UNITED STATES PATENT OFFICE.

WILLIAM T. CLINGER, OF OIL CITY, PENNSYLVANIA.

FIELD-GUN.

1,301,820.

Specification of Letters Patent. Patented Apr. 29, 1919.

Application filed September 5, 1918. Serial No. 252,742.

To all whom it may concern:

Be it known that I, WILLIAM T. CLINGER, a citizen of the United States, residing at Oil City, in the county of Venango and State 5 of Pennsylvania, have invented certain new and useful Improvements in Field-Guns, of which the following is a specification.

This invention relates to improvements in portable field guns designed primarily to 10 distribute the shots over a wide area at a remote point.

A further object of the invention is to provide means for mounting the guns so as to permit of convenient movement from 15 place to place, and means for locking the guns to the wheels to form an integral structure or abutment when the guns are fired.

A still further object of the invention is to provide a structure capable of simultaneously 20 firing a large number of shells to be effective over a wide range, making the gun particularly useful for defensive action against air bombing, or for field use.

The invention also comprehends improvements 25 in the details of construction and arrangement of parts which will be herein-after described, and particularly pointed out in the claims.

In the accompanying drawings:—

Fig. 1 is a side elevation of my improved gun.

Fig. 2 is a detail perspective view of the gun frame.

Fig. 3 is a central vertical section.

Fig. 4 is a top plan view.

Fig. 5 is a side elevation of a modified form of the invention.

Fig. 6 is a detail perspective view of a portion of the frame.

1 indicates a frame provided with two inwardly extended alined trunnions 3—3, which support wheels 4—4. The frame comprises a central elongated open yoke 5, located intermediate the wheels 4. The open 45 yoke extends above and below the horizontal plane of the trunnions, and from opposite sides of the upper bar 6, extend similar brackets 7—7. Each bracket projects over the top of the adjacent wheel, and then 50 depends on the outside of the latter as shown at 7, and from the inner side of the depending portion 8, projects the trunnion. Extending rearwardly from the lower ends of

the depending portions 8, are handles 9—9, and mounted on the same are brake shoes 55 9a, controlled and operated by levers indicated at 10.

When the brake shoes are applied to the wheels, the frame and wheels are made rigid, to form a fixed support for the guns, 60 as will later appear.

The forward vertical bar 11, of the frame 1, is provided with openings 12, to receive the barrels of machine guns 13, while the rear vertical bar 14, is provided with elongated 65 openings 15, in alinement with the openings 12, said openings receiving the stocks of the guns. Adjacent each opening 15, is a latch 16, to engage a notch 17, in the side of each gun stock, to hold the guns in 70 fixed position in the frame.

Pivottally mounted on the bar 14, adjacent the openings 15, are bell crank levers 17a, the horizontal members of which are all connected to a cable 18. The cable 18, passes 75 over a guide pulley 19, on the lower end of the frame, and thence passes over a guide 20, on one of the handles, and at its free end it is provided with a finger piece 22. The upper ends of the vertical members of the bell 80 crank levers are connected by links or the like 23, with the trigger 24, of the machine guns, as shown in Fig. 3, whereby to provide means for simultaneously firing all the guns. Shields 25, are mounted on the trunnions 85 inside the wheels, to protect the frame and the guns.

In the modification shown in Figs. 5 and 6, the frame 30, is pivoted at 31, to a platform 32, rotatably mounted on a base 33, 90 which is vertically adjustable by a rack and pinion such as shown at 34. The platform may be rotated and adjusted by means of the latch and teeth 35.

Extending vertically from the platform 95 32, is a standard 36, which supports a rack 37, coöperating with the rack is a pawl 38, pivoted to the frame 30, and connected to said pawl is a cable 39, which extends over a guide pulley 40, and its free end is secured to a block on the frame in convenient reach of the operator.

The frame is provided with alined elongated openings 41, through which the machine guns extend. The guns are retained in 105 the frame by latches 42, similar to those pre-

viously described, and the bell cranks and connections are likewise similar.

An L-shape standard 45, is mounted on the base, and the horizontal member thereof is provided with teeth 46. The horizontal member passes through a guide 47, which houses a pinion 48, to engage the teeth 46, whereby to move the L-shape bar back and forth. The vertical member of the L-shape bar is provided with sets of openings 50, through selected ones of which pins 51, pass, to pivotally connect links 52, the opposite ends of the latter being pivoted to the guns. By adjusting the pins 51, in selected openings the angular position of the various guns can be set to shoot over a wide area, and by rotating the pinion and moving the L-shape bar, the guns will be raised and lowered to increase or decrease the area over which the shots are intended to cover, the latches acting as pivots for the guns when this adjustment is made.

In operation, referring especially to Figs. 1 to 4, the machine guns are loaded, and inserted in the openings in the frame, the latches 16 are engaged in their seats, and the links 23 are connected to the triggers 24. The operator now releases the brakes, and the frame 1 is adjusted on the trunnions, to appropriately incline the guns to obtain the desired range. After the range is obtained, the brakes are set and the frame and wheels are locked together, and if need be, the wheels can be chucked.

The operator now pulls on the cable 18 and all the guns are simultaneously fired, and it follows that the shells are distributed over a wide range, this being especially desirable if the enemy's stand is on a hill side. By this construction of the frame and handles, it is obvious the guns may be elevated or depressed to shoot at any angle, which is particularly useful not only for attacking an enemy on a hill side, but is also advantageous for shooting at air craft when making raids.

The operation of the construction shown in Figs. 5 and 6 is somewhat similar to that just described, except that the frame is adjusted on the base, and is tilted for loading. In addition, by setting the pins and links, the angular disposition of guns with reference to each other to concentrate or widen the effective range of the guns can be conveniently made. Furthermore, the pawl and ratchet provides for angular adjustment of the guns, which of course is in addition to the angular adjustment of the individual gun.

What I claim is:—

1. In combination, a vertically disposed frame formed with aligned front and rear openings, a plurality of guns mounted in the aligned openings in the frame, means for an-

gularly adjusting the frame and guns, means 65 for supporting the frame, means for locking the frame in adjusted angular position, and means connecting all the guns to simultaneously fire all said guns.

2. In combination, an open frame, wheels 70 for supporting the frame, guns mounted in the frame, handles extending from the frame, brakes between the handles and the wheels to lock the latter and the frame together, and means for simultaneously firing 75 all the guns.

3. In combination, an open frame, wheels on which the open frame is pivotally supported, the frame having aligned openings, guns mounted in the openings, means for 80 locking the frame and the wheels together, a plurality of connected levers on the frame, and means for connecting the respective levers with the triggers of the respective guns whereby to simultaneously fire the 85 guns.

4. In combination, a pair of wheels, a frame disposed between the wheels and provided with overhanging brackets which extend over the wheels, a pair of trunnions on 90 the brackets, the wheels being supported on the trunnions, handles extending from the frame, brakes on the handles and disposed to engage the wheels, guns mounted in the frame, means for securing the guns to the 95 frame, and a plurality of connected devices on the frame and connected with the triggers of the guns whereby the guns are simultaneously fired.

5. In combination, a frame comprising a 100 central open yoke having aligned openings, lateral brackets extending from the upper end of the frame and depending at their ends, the depending portions having trunnions and rearwardly extended handles, 105 wheels mounted inside the brackets on the trunnions, brakes between the handles and the wheel, guns mounted in the frame, and means extended to one of the handles to 110 simultaneously fire all the guns.

6. In combination, side supports, a frame pivotally mounted on the side supports including a pair of depending bars formed with aligned openings to receive a plurality of guns, means for angularly adjusting the 115 frame, means for locking the frame when adjusted to the side supports, a trigger operating device adjacent each opening in one of the bars, and a connection between all the trigger operating devices to simultaneously fire the guns.

7. In combination, a support, a frame pivotally mounted on the support and including a pair of vertically disposed bars formed with a plurality of aligned openings 125 to receive a plurality of guns, a trigger operating device extending through each of the openings in one of the vertically dis-

posed bars, a connection between all the trigger operating devices, and means for locking the frame to support.

8. In combination, a pair of wheels, a frame having trunnions on which the wheels are mounted, said frame including a pair of spaced intermediate bars formed with a plu-

rality of alined openings to receive a plurality of guns, means on the frame for simultaneously firing the plurality of guns, 10 and means for locking the frame to the wheels.

In testimony whereof I affix my signature.
WILLIAM T. CLINGER.
